J. H. WIRT, OF DELPHI, INDIANA.

Letters Patent No. 77,153, dated April 21, 1868.

IMPROVED CONCRETE-BRICK PRESS.

The Schedule referred to in these Letters Patent and making part of the same.

TO ALL WHOM IT MAY CONCERN:

Be it known that I, J. H. WIRT, of Delphi, in the county of Carroll, and State of Indiana, have invented a new and improved Concrete-Block Press; and I do hereby declare that the following is a full, clear, and exact description thereof, which will enable others skilled in the art to make and use the same, reference being had to the accompanying drawings, forming part of this specification.

Figures 1 and 2 are sectional elevations of my press, taken through the lines *x x* and *y y*, respectively. Similar letters of reference indicate corresponding parts.

This invention relates to the pressing of concrete blocks for building purposes. It consists of the mechanism now to be described, by reference to the drawings, in which—

A is the general frame of the press, and the moulds at the top of the same, which contain the block or brick, *B*. The bottom of these moulds consists of stout pieces of wood, *u*, which are affixed across the upper end of the uprights *d*. These bottoms fit within the moulds, as shown, and rest upon cleats, *g*. The uprights pass through the plank *m*, which serves as guide to the former.

When moulds are filled with the concrete material, they are covered by a sliding top, *C*, which is operated by the lever *D*, and connecting-rod *E*, the latter being pivoted in a slot in the lever, and attached to the top, *C*, with a loose joint, whereby the same can be operated without cramping. The compound toggle-joint consists of the lever *a*, the link-rod *e*, the foot-lever *h*, and the toggle-bar *k*, across the top of which latter is affixed a cross-piece, *f*, on which the uprights *d* rest.

The ends of the cross-piece *f* work in slots in the part *A'* of the frame of the machine. The link-rod passes through the slot *l*, in the toggle-bar, and is pivoted in the slot *n* of the lever *a*, as shown, for the purpose of allowing the parts the maximum vibration in the same vertical plane. The lever *a* is notched at its lower end for the purpose of resting upon the bearing-roller *o*, as shown.

The lever *D* is mortised into a rocking-shaft, *p*, having bearings as shown. On the inner side of each of the uprights *d*, is a projection, *q*, for the purpose of enabling the compressed block to be lifted to the top of the moulds.

A lifting-lever, *G*, is used for this purpose, the said lever having forked ends, *r*, and cross-piece, *s*, which enclose one of the uprights loosely, so that the cross-piece *s* may be brought under either of the projections *q*, as shown.

In operating my machine, the moulds are filled with the concrete material, and the top, *e*, thrust forward by its lever *D*, as before described. The lever *a* is then depressed to the extent of its vibration, which will, by means of the compound toggle-joint, before described, actuate the bottoms upward against the concrete material within the moulds, and compress the same into a firm, solid block. This being done, the top, *e*, is withdrawn from over the moulds, and the lever *G* is adjusted so as to bring its cross-piece *s* under one of the projections *q*, and then depressed, which lifts the bottom, *a*, to the top of the moulds, and presents the block above the same for removal. The same operation follows with the other block, when all the levers are returned to their first positions, and the moulds again filled.

The lifting-lever *G* may rest upon the cross-piece *v*, affixed to the frame to act as a fulcrum, as it may be pivoted to a vibrating upright, arising from a rocking-shaft, as shown at the red outline of fig. 2.

This machine is more simple in its construction than those toggle-presses heretofore made, and can be produced at a small comparative cost. It is durable and efficient, and supplies a want long felt by those interested in the manufacture of concrete blocks for building purposes.

I claim as new, and desire to secure by Letters Patent—

1. The compound toggle-joint, consisting of the toggle-bar *k*, link-rod *e*, step-lever *h*, and lever *a*, substantially as shown and described, in combination with the uprights *d* and bottoms *u*, for the purpose of compressing concrete-blocks, all arranged as set forth.
2. The press, constructed as described, and consisting of the moulds *b*, cover *C*, link *E*, lever *D* *p*, bottoms *u*, uprights *d* *q*, guide *m*, lever *G* *r* *s*, toggle-bar *k* *f* *l*, step-lever *h* *i*, link *e*, and lever *a*, all arranged within the frame *A*, and operating in the manner and for the purpose set forth.

J. H. WIRT.
